HYDROCRACKING OF A PETROLEUM FRACTION WITH A SILICA-ALUMINA-COMPOSITE CRACK- ING CATALYST

Robert M. Kennedy, Newtown Square, and Alfred E. Hirschler and Conard K. Donnell, Springfield, Pa., assignors to Sun Oil Company, Philadelphia, Pa., a corporation of New Jersey

Application September 2, 1953, Serial No. 378,024

3 Claims. (Cl. 208—111)

This invention relates to the conversion of hydrocarbons. More particularly, the invention relates to a process of hydrocracking a specific hydrocarbon fraction boiling above the gasoline range to produce a high yield of high octane gasoline.

The conversion of various petroleum hydrocarbon fractions by processes such as cracking, reforming, hydro-forming, and the like, using a variety of catalysts and reaction conditions, has been described. Such heretofore described processes, however, are not suitable for converting the hydrocarbon fraction boiling substantially within the range of from about 375 to 500° F. to high octane gasoline in a single stage. Instead of achieving a good yield of high octane gasoline, there is produced gasoline hydrocarbons of relatively low octane rating usually in low yields, the production of normally gaseous hydrocarbons, such as propanes and butanes, is excessive, and the reduction of catalyst activity is rapid. It has heretofore been necessary to employ at least two stages to convert a fraction boiling above the gasoline range to high octane gasoline. Such processes usually involve a cracking stage wherein a portion of the hydrocarbons are converted to hydrocarbons boiling in the gasoline range, and a reforming, or hydroforming, stage to upgrade the octane number of the gasoline. In the upgrading stage, the use of two catalysts in separate reactors with a hydrocarbon separation step between the reactors, or the use of two catalysts in a single reactor, has heretofore commonly been required.

An object of the present invention is to provide a single stage process for converting a petroleum hydrocarbon fraction boiling substantially within the range of from 375 to 500° F. to high octane gasoline in good yield. A further object is to provide a process for converting higher boiling hydrocarbons to high octane gasoline hydrocarbons wherein only minor quantities of normally gaseous hydrocarbons are formed, and wherein catalyst activity is maintained over long reaction periods. A still further object is to integrate the use of specific catalysts with a combination of reaction conditions to provide a process whereby higher boiling hydrocarbons are converted in a single stage to gasoline hydrocarbons of high octane number. Other objects will be apparent from the following specification.

It has now been found that a petroleum hydrocarbon fraction boiling substantially between 375 and 500° F. can be converted in good yield to high octane gasoline by contacting the fraction with a specific catalyst under specific and correlated conditions of temperature, pressure, space velocity, and hydrogen to hydrocarbon ratio.

In accordance with the present invention, a petroleum hydrocarbon fraction boiling substantially within the range of from about 375 to 500° F. is contacted with a specific catalyst consisting essentially of silica, alumina, and molybdenum oxide or chromium oxide, as herein-after defined, at a temperature of from 795° F. to 935° F., a pressure of from 500 to 1500 p. s. i. g. (pounds per square inch gauge), a space velocity of from 0.5 to 5 and a hydrogen to hydrocarbon mole ratio within the range of about 1:1 to 20:1. By operating within the stated

2

limits with the specific catalysts of the invention, a conversion of the charge stock of at least 25 volume percent, based on the liquid charge, to gasoline having an octane number of at least 83 (research octane, clear) is achieved

5 over periods of at least 70 hours of continuous operation.

A change of the catalyst or of any variable outside of the stated range may give a low yield, say 10 volume percent, of high octane gasoline, or a relatively high yield of low octane gasoline, and in either event such operation 10 is considered inoperative and outside of the scope of the present invention, which is directed to a process of obtaining high yields (above 25 volume percent) of high octane (above 83) gasoline over long periods of continuous operation (at least 70 hours).

15 The process of the present invention can conveniently be designated as "hydrocracking." By "hydrocracking," as used herein, is meant a process including the following reactions: (1) hydrocarbons boiling substantially within the range of from 375 to 500° F. are cleaved to form

20 lower molecular weight hydrocarbons boiling within the gasoline range, which is usually from about 80° F. to 350° F., but which can have an upper boiling point as high as about 430° F.; (2) naphthenes having a ring composed of 6 carbon atoms are dehydrogenated to form

25 aromatic hydrocarbons; (3) paraffins are isomerized to branched or more highly branched paraffins, and naphthenes having a ring of 5 carbon atoms appear to be isomerized to naphthenes having a 6 carbon atom ring, which are then dehydrogenated to aromatics; (4) olefins, 30 normally produced in the cracking processes, are hydrogenated to saturated hydrocarbons.

As above stated, a specific catalyst is employed in the present process. The catalyst consists of a synthetic silica-alumina cracking catalyst having deposited thereon from 2.9% to 11% molybdc oxide. Chromic oxide can be substituted for molybdc oxide as hereinafter explained. Synthetic silica-alumina compositions are well known as cracking catalysts, and heretofore described methods for their preparation may be employed in preparing the silica-alumina portion of the present catalyst.

For example, the silica-alumina portion of the catalyst may be prepared by impregnating silica with aluminum salts, by directly combining precipitated hydrated alumina and silica, or by joint precipitation of alumina and silica from aqueous solutions of their salts, and by washing, 35 drying, and heating the resulting composition. In order for the resulting silica-alumina composition to give satisfactory results in the process of the present invention, it must have an activity index of at least 40, and preferably

40 from about 40 to 50, prior to depositing molybdc or chromic oxide thereon. "Activity index," as used herein, is a measure of the efficacy of a catalyst for cracking hydrocarbons and is determined by a method described by Alexander, Proceedings Am. Pet. Inst. 27 (III) 51 (November 1947). Molybdc oxide or chromic oxide is deposited on this silica-alumina composition. The deposition 45 may be in accordance with methods known to the art. For example, aqueous solutions of water soluble compounds of molybdenum or chromium, such as ammonium molybdate and chromium nitrate, may be employed to impregnate the silica-alumina composition. The resulting impregnated composition is then heated to convert the salt employed to the corresponding oxide, either

50 molybdc oxide or chromic oxide.

55 As above stated, the concentrations of the catalytic components are important, and the concentration of each component must be within a defined range. When employing molybdc oxide, the concentration thereof must be in the range of from 2.9 to 11% by weight of the final composition. When employing chromic oxide the concentration thereof must be between 6 and 20% by weight of the final composition. The critical nature of

these limits are shown hereinafter by example. The silica-alumina composition on which the molybdenum or chromium oxide is deposited must consist of from 50 to 90% by weight silica and from 50 to 10% by weight alumina. The final catalytic composition thus contains, in percent by weight, from about 45 to 87.5% silica, from about 9 to 48.6% alumina, and from about 2.8 to 10% molybdc oxide. When using chromic oxide the final composition contains, in percent by weight, from about 41.7 to 85% silica, from about 8.3 to 47.2% alumina, and from about 5.6 to 16.6% chromia.

Metals and metallic oxides, other than the oxides of molybdenum or chromium, and carriers other than the synthetic silica-alumina compositions described above, do not give satisfactory results in the process. For example, vanadium oxide on a silica-alumina composition as above described, 5% molybdc oxide deposited on a synthetic silica-alumina composition having an activity index of 28, or on a clay mineral having a cracking index of 40, do not give satisfactory results.

The temperature to employ must be within the range of from 795° to 935° F. At temperatures above 935° F., a large amount of normally gaseous hydrocarbons are produced in the process, and the yield of gasoline hydrocarbons is low. At temperatures below 795° F., aromatic hydrocarbons are hydrogenated in the process. This is an undesired reaction which causes a reduction in the octane rating of the gasoline fraction. A temperature of substantially 887° F. is preferred, since this temperature converts the higher boiling fraction into high octane gasoline in good yield, only minor quantities of normally gaseous hydrocarbons being formed.

The pressure to employ in the present process must be maintained within the range of from 500 to 1500 p. s. i. g. At pressures below 500 p. s. i. g., the activity of the catalyst rapidly decreases because of excessive coke formation thereon. At pressures above 1500 p. s. i. g., aromatics are hydrogenated to naphthenes. If higher temperatures are employed to overcome this undesired hydrogenation obtained at high pressures, a large conversion to normally gaseous hydrocarbons, instead of to gasoline hydrocarbons, is observed. In general, relatively high pressures of from about 1000 to 1300 p. s. i. g. are preferred, since as shown hereinafter by example, the gasoline yield is enhanced thereby.

The space velocity must be maintained within range from 0.5 to 5. It is preferred to employ a space velocity of substantially 1 to 2, since there is obtained a high gasoline yield of high octane number, and very low conversion of hydrocarbons to normally gaseous hydrocarbons. At space velocities below 0.5, a high yield of normally gaseous hydrocarbon is obtained, and at space velocities of above 5, the yield of gasoline is adversely affected. By "space velocity," as used herein, is meant the liquid hourly space velocity, which is the liquid volume of hydrocarbons charged per volume of catalyst per hour.

The process of the invention converts petroleum hydrocarbon fractions boiling in the range of from 375 to 500° F. in good yield to high octane gasoline hydro-

carbons. The process is not operable with other fractions, such as for reforming a gasoline fraction, as shown hereinafter by example, or for converting a fraction boiling above 500° F. The fraction to employ preferably boils over a range of at least 60° F. with an initial boiling point of at least 375° F. and an end point not above 500° F. The fraction should have at least 10% by volume naphthenes, and preferably has from 12 to 60% by volume naphthenes. Olefins may be present and do not appear to deleteriously affect the process, but in the preferred straight run petroleum the concentration thereof is usually less than about 3% by volume.

The presence of hydrogen is absolutely essential to the process. The mole ratio of hydrogen to hydrocarbons charged, however, can be substantially varied and good results obtained therewith. Within the limitations of the several variables of operation, as above described, the hydrogen to hydrocarbon mole ratio can be varied from 1 to 20 with good results. The preferred conditions of operation are such that the hydrogen partial pressure is within the range of from about 800 to 1400 p. s. i. g.

The following examples illustrate the process of the invention and demonstrate the critical nature of the limitations as set forth above. In the tables, under "Yield of Products," the dry gas yield is given in weight percent of the charge stock and butane and gasoline yields are given in volume percent of the liquid charge, unless otherwise stated. As used in the examples and tables, "gasoline" is the debutanized fraction boiling up to 350° F., i. e. is the fraction containing pentanes and boiling up to 350° F. "Research octane, clear," is determined by ASTM Test D 908, and "research octane+1.5 cc. TEL" (tetra ethyl lead) is determined by the same test with the stated quantity of TEL added to the gasoline. The most frequently used and preferred catalyst of the examples consists essentially of a silica-alumina cracking catalyst having deposited thereon 5% MoO_3 . The silica-alumina cracking catalyst prior to deposition of MoO_3 contains 11% alumina and 89% silica, has a cracking index of 46 and was prepared by coprecipitation, washing, and drying. The molybdc oxide was deposited on this cracking catalyst by impregnating the silica-alumina composition with an aqueous solution of ammonium molybdate, drying and heating the resulting composition to a temperature of about 1100° F. In the following examples and tables this final catalyst is identified as "catalyst A."

EXAMPLE 1
To illustrate a preferred embodiment of the process of the invention, catalyst A was used to hydrocrack a straight run petroleum fraction boiling between 400 and 500° F. The charge fraction was composed, in volume percent, of 18% aromatics, 28% paraffins, 40% monocyclic naphthenes, 13% dicyclic naphthenes, and a small amount of other materials. The petroleum fraction, at a space velocity of 1, admixed with hydrogen was contacted with a catalyst maintained at a temperature of 887° F., and at a pressure of 1000 p. s. i. g. The hydrogen to hydrocarbon mole ratio, and results obtained, are shown in Table I.

¹ Catalyst regenerated, by burning off carbon, after 70 hours' operation.

As shown by the table, the process of the present invention gives a high yield of high octane gasoline for many hours. Catalyst regeneration, as shown in the table, after 70 hours of operation, does not adversely affect the process. Thus, the gasoline yield was above 25 volume percent 188 hours after regenerating the catalyst.

perature of 887° F., a pressure of 1000 p. s. i. g. and a space velocity of 1. The hydrogen to hydrocarbon ratios employed are shown in following Table II, as are other pertinent operating conditions and data obtained. The yield of debutanized gasoline of 350° F. end point, as a function of time, is shown in the accompanying figure.

lyst. The high octane number and good lead susceptibility of the gasoline fraction show the excellent results achieved in accordance with the process of the present invention. The relatively low yields of dry gas and butanes are also to be noted. These products are valuable, however, so that their formation in minor quantities is not disadvantageous. The dry gas can be used as a fuel and the butanes, consisting of a mixture of normal and isobutane, can be used in processes such as alkylation to form valuable hydrocarbons, or the butanes may be included in the gasoline fraction especially when the gasoline is to be used in cold weather engine operation.

EXAMPLE 2

Three catalysts were prepared by depositing various quantities of molybdc oxide on a silica-alumina cracking catalyst having about 11% Al₂O₃ and 89% SiO₂. Prior to the deposition of molybdc oxide, the cracking catalyst had a cracking index of 46. The quantities of molybdc oxide deposited on the silica-alumina catalysts were 2.9% (catalyst B), 4.4% (catalyst C) and 10.2% (catalyst D). The catalysts were employed, under comparable conditions, for hydrocracking a straight run petroleum fraction. The straight run charge stock had the following boiling characteristics: an initial boiling point of 410° F., 10% distilled at 418° F., 50% distilled at 449° F., 90% distilled at 472° F., and an end point of 490° F. The average molecular weight of this charge stock was 185, and it was composed of 16 volume percent aromatics, 30 volume percent paraffins, 41 volume percent monocyclic naphthenes, 12 volume percent di-cyclic naphthenes, and 1 volume percent of other materials.

All of the runs of this example were made at a tem-

30 As shown by the data and figure, catalyst B gives a good yield of gasoline for a short time, but rapidly loses its initially high activity. Catalyst D gave a relatively low yield of gasoline throughout the run. Catalyst C, containing 4.4% MoO₃, gave good results and maintained high activity for many hours. Thus, after 100 hours of operation, catalyst C was giving a steady yield of about 35% gasoline, while catalysts B and D were giving a yield of about 25%. For comparison, the data obtained with the silica-alumina catalyst without MoO₃ deposited thereon is included in the figure. If a gasoline fraction of a wider boiling range is desired, say a fraction having an end point of 400° F., the yield obtained in the process is increased accordingly. When amounts of molybdc oxide below 2.9%, or above 11%, are employed, the yield of gasoline rapidly decreases to below 25% so that the process is rendered inoperative thereby. Hence the quantity of molybdc oxide deposited on the silica-alumina composition must be from 2.9 to 11% by weight of the silica-alumina composition.

EXAMPLE 3

50 In order to demonstrate the use of chromic oxide in place of molybdc oxide, two catalysts were prepared. One catalyst contained 11% chromic oxide, 28% alumina, and 61% silica (catalyst E), the other containing 9.1% chromic oxide, 10% alumina, and 80.9% silica (catalyst F). The activities of both of the silica-alumina compositions employed, prior to the depositions of chromic oxide thereon, were above 45. The procedure and charge stock of Example 1 were employed using a temperature of 887° F., a pressure of 1000 p. s. i. g., and a space velocity of 1. The hydrogen to hydrocarbon mole ratios and results obtained are shown in the following Table III.

Table III

Hours on stream	Catalyst E			Catalyst F			
	0-30	30-54	54-78	0-24	24-48	48-72	72-78

TEL	93.4	92.3	91.9	94.0	92.8	92.9	

As shown by Table III, both catalyst E and catalyst F gave a high octane gasoline in good yield after more than 70 hours' operation.

EXAMPLE 4

In order to demonstrate the failure of catalysts other than those herein claimed to give comparable results in the present process, various catalytic compositions heretofore described as effective in processes such as hydro-cracking and reforming were prepared. Catalyst G consisted essentially of 5% vanadium oxide deposited on the same silica-alumina cracking catalyst as used for catalyst

tively low cracking index. Catalyst L consisted of 5.1% of MoO_3 deposited on acid activated montmorillonite. Prior to deposition of molybdc oxide, the montmorillonite had an activity index of 40. Catalyst M consisted essentially of 10% chromic oxide deposited on the same silica-magnesia composition as catalyst J, which was a commercially available silica-magnesia cracking catalyst. In each instance the charge stock was the same as employed in Example 2 and the same conditions of operation were employed except as otherwise indicated in Table V. The data obtained are as shown by Table V.

A. Catalyst H consisted essentially of 7.3% boric oxide on alumina. Catalyst I consisted essentially of 0.5% platinum deposited on a silica-alumina cracking catalyst having a cracking index, prior to the deposition of platinum thereon, of about 30. Catalyst J consisted of 0.5% platinum deposited on a commercially available silica-magnesia cracking catalyst. The hydrogen to hydrocarbon mole ratio and results obtained therewith are shown in the following Table IV. Each catalyst was run with the same hydrocarbon charge stock as Example 2 under the same conditions therein described except as otherwise indicated in the table.

As will be noted from the data, very poor results were obtained with each of these catalyst. Thus, using vanadium oxide, a poor yield of gasoline was obtained and the quality of the gasoline rapidly decreased. Using boria on alumina the yield of gasoline was insignificant. Using platinum on a silica-alumina cracking catalyst having an activity index of 30 gave a low octane gasoline product as did the other platinum catalyst.

As shown by the table, silica-alumina compositions having a cracking activity of less than 40 do not give good results, and natural minerals, used in place of synthetic silica-alumina compositions, do not give good results. Thus, catalyst K gave a poor yield of gasoline and catalysts L and M gave low octane gasoline.

EXAMPLE 6

In order to illustrate the importance of maintaining the quantity of alumina in the synthetic silica-alumina composition within the range of from 10% to 50% thereof, the following catalysts were prepared. Catalyst N consisted essentially of 5.4% MoO_3 on a synthetic silica-alumina cracking catalyst containing 32% alumina and 68% silica; the cracking catalyst prior to deposition of molybdc oxide had an activity index of about 50. Catalyst O consisted of 19% chromic oxide, 25.5% silica and 55.5% alumina, which, for comparison, is the equivalent of having about 23.5% chromia deposited on a composition consisting of 31.5% silica and 68.5% alumina. It

¹ A space velocity of 4, instead of 1, was used.

EXAMPLE 5

In order to demonstrate the importance of employing a synthetic silica-alumina cracking catalyst having an activity index of above 40, and of maintaining the silica-alumina ratio within the stated value, various catalysts were prepared as follows: Catalyst K was prepared by depositing 5% MoO_3 on a synthetic silica-alumina cracking catalyst having a cracking index of about 30; this catalyst was identical to catalyst A except for the rela-

70 will be noted that the composition of catalyst O is outside the scope of the invention. Catalyst Q consisted essentially of 10% molybdc oxide, 6.5% silica and 83.5% alumina, which, for comparison, is the equivalent of having about 11% molybdc oxide deposited on a composition consisting of 7.2% silica and 92.8% alumina, which of course is outside the scope of the invention. Results obtained, following the procedure of Example 2, are shown in the following Table VI.

Table VI

¹ Temperature of 932° F. used instead of 887° F.

It will be noted that catalyst N gave good results, the proportions of catalyst constituents being within the defined ranges. Catalysts O and P were inoperative in the process, the proportions of catalyst constituents being outside the defined ranges.

EXAMPLE 7

In order to show the importance of maintaining the

straight run petroleum fraction boiling between 375 and 460° F., having 12.9 vol. percent aromatics, 1.1 vol. percent olefins, 0.031 wt. percent sulfur, and the remainder being naphthenes and paraffins, was employed in the process following the procedure of Example 1. The hydrogen to hydrocarbon mole ratio was maintained within the range of from 13.7 to 14.2. Results obtained are shown in the following Table VIII.

Table VIII

charge stock boiling range within the limits herein described, the procedure of Example 1 was repeated, using catalyst A. The charge stock was a straight run petroleum fraction boiling between 250 and 500° F. This fraction contained 53.1 volume percent gasoline, i. e. hydrocarbons boiling between 250 and 350° F. Results obtained are shown in the following Table VII.

In order to illustrate the effect of temperature in the present process, the procedure of Example 1 was repeated at temperatures of 932° F. and 752° F., using catalyst A. The data obtained are shown in the following Table VIII. At 932° F., a good yield of high octane gasoline was

¹ 500 p. s. i. g. instead of 1,000 p. s. i. g.

It will be noted that the octane number of the product was very low as was the gasoline yield, after allowance for the hydrocarbon boiling in the gasoline range introduced by the charge stock. The formation of dry gas and butanes was actually greater than the incremental increase in gasoline.

EXAMPLE 8

To show a preferred embodiment of the invention, a

70 obtained, but there was also obtained a relatively large quantity of dry gas and butanes. At 752° F., which is below the minimum temperature required in the process, the octane number of the gasoline products was so low as to render the process inoperative.

These data show the importance of maintaining the temperature of the process of the present invention within the limits of from 795 to 935° F.

EXAMPLE 10

In order to illustrate the importance of pressure and space velocity, the procedure of Example 1 was repeated using 1200 p. s. i. g. and space velocity of 1 and 2 respectively. The data obtained are shown in the following Table X.

As shown by the table, a good yield of high octane gasoline was obtained with this charge stock, showing that the charge stock can be recycled to substantial extinction.

The invention claimed is:

1. Process of hydrocracking a petroleum hydrocarbon

¹ 1,200 p. s. i. g. instead of 1,000 p. s. i. g.

² Space velocity=2 instead of 1.

As shown by the table, the use of high pressure and a space velocity of 1 results in high gasoline yield with a good octane number. Using the same pressure and increasing the space velocity to 2, the gasoline yield drops while the octane number is improved considerably. Both of these examples are within the scope of the process of the invention. At pressures above 1500 p. s. i. g., the octane number is too low probably because of the hydrogenation of naphthenes and at space velocities of above 5, the process is inoperative in that the yield of gasoline is very low.

EXAMPLE 11

In order to demonstrate the use of unconverted or insufficiently converted hydrocarbons in the process as recycle charge stock, hydrocarbons boiling from about 400 to 500° F. separated from the gasoline product of previous runs, performed in accordance with the process of the present invention, were used as charge stock together with catalyst A and the same conditions employed in Example 1. The results obtained are shown in the following Table XI.

fraction boiling within the range of from 375° F. to 500° F. and containing at least 10% by volume naphthenes, which comprises contacting an admixture of said fraction and hydrogen with a catalyst consisting essentially of a synthetic silica-alumina cracking catalyst having a cracking index of at least 40, a silica content of from 50 to 90%, and an alumina content of from 50 to 10%; said silica-alumina cracking catalyst having deposited thereon a material selected from the group consisting of molybdc oxide in an amount of from 2.9% to 11% of said silica-alumina catalyst and chromic oxide in an amount of from 6% to 20% of said silica-alumina catalyst, said contacting being at a temperature of from 795° F. to 935° F., a pressure of from 500 to 1500 p. s. i. g., a space velocity of from 0.5 to 5, and a hydrogen to hydrocarbon mole ratio of from 1:1 to 20:1, and separating from the reaction products a gasoline fraction having an octane number of at least 83.

2. Process of hydrocracking a petroleum hydrocarbon fraction boiling within the range of from 375° F. to 500° F. and containing from 10% to 60% by volume naphthenes which comprises contacting an admixture of said fraction and hydrogen with a catalyst consisting essentially of a synthetic silica-alumina cracking catalyst having a cracking index of at least 40, a silica content of from 50 to 90% and an alumina content of 50 to 10%, said silica-alumina cracking catalyst having deposited thereon from 2.9 to 11% molybdc oxide, said contacting being performed at a temperature of from 795° F. to 935° F., a pressure of from 500 to 1500 p. s. i. g., a space velocity of from 0.5 to 5, and a hydrogen to hydrocarbon mole ratio of from 1:1 to 20:1, continuing said contacting for a continuous period of at least 70 hours, and separating from the reaction products a gasoline fraction in a yield of at least 25 volume percent, based on the liquid
